C. C. EGBERT.

PRESSURE RELIEF DEVICE.
APPLICATION FILED JULY 23, 1920.

Patented Oct. 18, 1921.

UNITED STATES PATENT OFFICE.

CHARLES C. EGBERT, OF NIAGARA FALLS, NEW YORK.

PRESSURE-RELIEF DEVICE.

1,394,072.

Specification of Letters Patent. Patented Oct. 18, 1921.

Application filed July 23, 1920. Serial No. 398,524.

To all whom it may concern:

Be it known that I, CHARLES C. EGBERT, a citizen of the United States of America, and a resident of the city of Niagara Falls, 5 county of Niagara, and State of New York, have invented certain new and useful Improvements in Pressure-Relief Devices, of which the following is a full, clear, and exact description.

10 My invention relates generally to safety devices, in the nature of bursting plugs, used to relieve the pressure within any receptacle and adapted particularly for use in connection with penstocks.

15 As is well known to those skilled in the art, the bursting plugs or plates used at present have a very small factor of safety. For example, assuming the normal pressure is three hundred fifty pounds per square 20 inch and that it is desired to have the plug or plate burst at four hundred fifty pounds, this would mean that there would be a factor of safety of 450/350 or only 1.29. Assuming 25 the ordinary surge in the penstock increases the pressure fifty pounds or to four hundred pounds per square inch, this only allows a factor of safety of 1.12. The result is that such ordinary surges will eventually weaken 30 the fastenings of the plate or the bolts there- of and cause them to frequently burst with the attending loss of service, and the expense 35 and annoyance in replacing the broken parts. Furthermore, the usual factor of safety, first above given, is so small that if the surge should be in excess of fifty pounds the plate is very likely to burst before the actual pres- 40 sure, at which it is set, has been reached.

The principal object of my invention has 45 been to provide a device which shall over- come the objections above set forth, and one in which it shall be possible to make the factor of safety large enough so that the device shall in no wise become weakened by the ordinary surges which occur in turbine pen- stocks.

Another object has been to provide a de- 50 vice of this nature having a nozzle which, when the cap at the end thereof has been blown off, will project the water in a well de- fined stream, so that it may be confined and discharged in a manner which will not cause injury by the impact or erosive action of the stream.

Another object has been to provide a de- 55 vice in which a sensitive relief valve may be employed in connection with an auxiliary

piston, whereby a well defined and easily controlled percentage of increase in pressure of the water within the penstock may be transferred to the auxiliary piston, and cause 60 the safety plug to be blown.

Another object has been to provide a de- vice in which the parts broken at each rup- ture shall be reduced to a minimum.

The above objects and advantages have 65 been accomplished by the device shown in the accompanying drawings, of which:

Figure 1 is a longitudinal, sectional view of my complete device, showing it attached 70 to a penstock.

Fig. 2 is an enlarged fragmentary view 75 of the same with slight modifications.

In the drawings, 5 represents the penstock in which water under pressure is conducted to a turbine. While I have shown and will 75 describe my invention in connection with a turbine penstock, it is obvious that the device is applicable to any receptacle carrying pressure. The penstock 5 is provided with a branch connection 6, to the flange 7 of 80 which is bolted the nozzle 8 of my device. The outer end of the nozzle 8 is preferably provided with a counterbore 9 in which is fitted the bursting plug 10. The bursting 85 plug is provided with an outwardly project- 90 ing flange 11. A plurality of bolts 12 are screw-threaded into the outer end of the nozzle 8, each having a head 13, by which the bolt may be screwed into the nozzle or removed therefrom when ruptured. The 95 heads 13 of these bolts lie preferably within a recess 14, provided between the end face of the nozzle and the inner face of the flange 11 of the bursting plug. The bolts 12 are extended outwardly and pass through aper- 100 tures 15 formed in the flange 11 of the plug 10, and each is provided with a nut 16, whereby the bursting plug is securely held in position. Each of the bolts 12 has a peripherally reduced portion 17, thereby giving 105 each bolt a breaking area which causes the bolt to rupture when subjected to the strain of a definite number of pounds and at a predetermined point in its length.

Surrounding the mouth of the nozzle 8 is 105 a cylinder flange 18, in which an annular cylinder 19 is provided. This cylinder opens toward the flange of the bursting plug 10 and within it is slidably mounted an annular piston 20. The inner diameter of the 110 annular piston 20 is somewhat less than the outer diameter of the flange 11 of the burst-

ing plug 10, so that the flange overhangs the piston 20. The parts are so designed that the face of the piston is in contact with the inner face of the flange 11 when the parts are 5 in their normal position as shown in the drawings.

Near the outer end of the cylinder, an annular groove 22 is provided. This groove is arranged some distance from the outer 10 face of the annular piston at its outer periphery and within the groove is arranged a retaining ring 23. This retaining ring 23 projects above the groove and into the cylinder 19, in which position it is held by a 15 plurality of bolts 24. This retaining ring acts as a stop to prevent the piston from being forced out of the cylinder when the device is in operation.

An annular recess 25 is provided at the 20 bottom of the cylinder 19. This annular recess is in communication with a port 26, formed in the casting of the nozzle 8 and terminating preferably at a flange 27. A port 28 is provided through the wall of the 25 penstock 5 and terminates at a flange 29. 30 is a relief valve. This is an article of standard commercial manufacture and need not, therefore, be described in this specification, except to state that it is of a type 30 which will operate within a very small percentage of a predetermined pressure. Connecting the inlet flange 31 of the relief valve with the flange 29 is a pipe 32, and connecting the outlet flange 33 of the relief valve 35 with the flange 27 is a pipe 34. By this arrangement the ports 26 and 28 are connected with each other through the relief valve 30. 36 is a by-pass pipe which has a valve 36 connected therein and by which fluid may be 40 allowed to pass from pipe 32 to pipe 34 without passing through the relief valve. By this means, the pipe 34; port 26 and the annular recess 25 may be filled with fluid, so that when the valve 30 responds to a pre- 45 determined increase in pressure, the piston 25 will be immediately acted upon in the least possible interval of time. This may be accomplished by providing a small leakage hole in the relief valve 30, but I prefer 50 to employ the controlled by-pass pipe 35 for this purpose. A drip pipe 37 is provided on the pipe 34 and prevents any possible leakage through the relief valve 30 or the by-pass pipe 35 from building up pressure 55 within the pipe 34, port 26 or annular recess 25. This drip pipe is made large enough so as to prevent the leakage referred to, but not so large as to materially reduce the pressure in the recess 25 when the relief 60 valve 20 operates.

The annular piston 20 in the face contacting with the flange 11 of the bursting plug is formed with a plurality of relief grooves 38 (Fig. 2), whereby any leakage of pressure 65 past the joint between the bursting plug 10

and the nozzle 8 will be prevented from passing between the piston and cylinder or building up pressure within the annular recess 14. If desired, the annular piston 20 may be chamfered at its inner and outer 70 corners, as shown in Fig. 2 of the drawings, where it may be provided with strips of suitable packing 39. If desired, however, the joint between the piston and cylinder may be so machined that packing shall be 75 unnecessary. The bursting plug 10 may also be similarly packed.

From the foregoing description, it will be understood that when the pressure of the fluid within the penstock 5 rises to the pre-determined amount, at which the relief valve 30 is set, the relief valve will operate and allow fluid to pass through port 28, pipe 32, pipe 34, port 26 and to the annular chamber 25, where its pressure will be exerted 80 against the bottom of the annular piston 20. This pressure together with that exerted against the bursting plug 10 will rupture the bolts 12 and blow the bursting plug 10 out of the end of the nozzle 8, thus relieving the 85 abnormal pressure within the penstock 5, and projecting the fluid passing through the nozzle in a well defined stream. The replacement of the bursting plug will, of course, require that the water from the nozzle 8 be shut off, either by shutting off the penstock 5 or by closing a shut-off valve placed between the nozzle 8 and the branch 6 of the penstock. The broken bolts 12 may then be removed and replaced by new ones 90 and the same or a new bursting plug put back in position.

By proportioning the area of the annular piston 20 with respect to the area of the relief cover 10, the bolts 12 may be reduced 105 at 17 to an area at which they will burst under the combined pressures on the annular piston and the bursting plug. By this means, the bolts may be made of a strength several times greater than the load imposed 110 upon them by the pressure of the fluid against the bursting plug only, and thus made safe against rupture under normal conditions of water pressure, as it requires the combined force of the pressure exerted 115 against both the bursting plug and annular piston to cause their rupture.

While I have shown and described the annular recess 25 and the annular piston 20 for exerting pressure against the flange 11 120 of the bursting plug, it is obvious that I may use a plurality of cylinders arranged about the nozzle 8 and each having a piston bearing against the flange 11. Instead of the retaining ring 23 fitting into the annular groove in the cylinder, it is clear that a flange may be bolted onto the face of the cylinder or a plurality of bolts passing through the cylinder may be used to limit the motion of the piston 20. These and 130

other modifications of the details herein shown and described may be made without departing from the spirit of my invention or the scope of the appended claims, and I
 5 do not, therefore, wish to be limited to the exact embodiment herein shown and described, the form described being merely a preferred embodiment thereof.

Having thus described my invention, what
 10 I claim is:

1. The combination with a receptacle containing fluid under pressure, of a pressure relief device characterized by having a bursting plug exposed to the fluid pressure within the receptacle, fastening means for the plug, having a relatively high factor of safety, and means for exerting an auxiliary pressure against the plug and the fastening means.
 15
 2. The combination with a receptacle containing fluid under pressure, of a pressure relief device characterized by having a bursting plug exposed to the fluid pressure within the receptacle, fastening means for the plug, having a relatively high factor of safety, means for exerting an auxiliary pressure against the plug and the fastening means, and a pressure relief valve for controlling the auxiliary pressure.
 20
 3. The combination with a receptacle containing fluid under pressure, of a pressure relief device characterized by having a bursting plug exposed to the fluid pressure within the receptacle, fastening means for the plug, having a relatively high factor of safety, auxiliary means for transmitting pressure to the plug, a pressure relief valve, and means connecting the receptacle with the relief valve and the auxiliary means.
 25
 4. The combination with a receptacle containing fluid under pressure, of a pressure relief device characterized by having a bursting plug exposed to the fluid pressure within the receptacle, fastening means for the plug, having a relatively high factor of safety, a cylinder located on the pressure side of the plug, a piston slidably mounted in the cylinder and normally bearing against the plug, and means, connected with the receptacle, for exerting a pressure against the piston.
 30
 5. The combination with a receptacle containing fluid under pressure, of a pressure relief device characterized by having a nozzle, a bursting plug covering the nozzle outlet and exposed to the fluid pressure within the receptacle, an annular cylinder surrounding the nozzle outlet, a piston slidably mounted in the cylinder and bearing against the plug, and means, connected with the receptacle, for exerting a pressure against the piston.
 35
 6. The combination with a receptacle containing fluid under pressure, of a pressure relief device characterized by having a nozzle, a bursting plug covering the nozzle outlet and exposed to the fluid pressure within the receptacle, an annular cylinder surrounding the nozzle outlet, a piston slidably mounted in the cylinder and bearing against the plug, and means, connected with the receptacle, for exerting a pressure against the piston.

60
 65
 66

zle, a bursting plug covering the nozzle outlet and exposed to the fluid pressure within the receptacle, an annular cylinder surrounding the nozzle outlet, a piston slidably mounted in the cylinder and bearing against the plug, a pressure relief valve, and means connecting the receptacle with the pressure relief valve and the annular cylinder.

7. The combination with a receptacle containing fluid under pressure, of a pressure relief device characterized by having a nozzle, a bursting plug covering the nozzle outlet and exposed to the fluid pressure within the receptacle, an annular cylinder surrounding the nozzle outlet, a piston slidably mounted in the cylinder and bearing against the plug, means carried by the cylinder for limiting the movement of the piston, and means, connected with the receptacle, for exerting a pressure against the piston.

8. The combination with a receptacle containing fluid under pressure, of a pressure relief device characterized by having a nozzle, a bursting plug covering the nozzle outlet and exposed to the fluid pressure within the receptacle, the plug being provided with a lateral flange forming a recess between it and the end of the nozzle, fastening means for the plug, passing through the recess, a piston normally bearing against the flange, the piston being provided with relief grooves in the face which contacts with the flange, and means, connected with the receptacle, for exerting pressure against the piston.

9. The combination with a receptacle containing fluid under pressure, of a pressure relief device characterized by having a nozzle, a bursting plug covering the nozzle outlet and exposed to the fluid pressure within the receptacle, an annular cylinder surrounding the nozzle outlet, a piston slidably mounted in the cylinder and bearing against the plug, the cylinder being formed with an annular recess at its bottom, and means connecting the receptacle with the recess for exerting a pressure against the piston.

10. The combination with a receptacle containing fluid under pressure of a pressure relief device characterized by having a nozzle, having a counterbore at its outer end, a bursting plug fitted into the counterbore and exposed to the fluid pressure within the receptacle, an annular cylinder surrounding the nozzle outlet, a piston slidably mounted in the cylinder and bearing against the plug, and means, connected with the receptacle, for exerting pressure against the piston.

11. The combination with a receptacle containing fluid under pressure, of a pressure relief device characterized by having a nozzle, a bursting plug covering the nozzle outlet and exposed to the fluid pressure within the receptacle, an annular cylinder

der surrounding the nozzle outlet, a piston 5 slidably mounted in the cylinder and bearing against the plug, a pressure relief valve, means connecting the receptacle with the relief valve and the annular cylinder, and a valve-controlled by-pass for conducting the fluid around the relief valve.

12. The combination with a receptacle containing fluid under pressure, of a pressure relief device characterized by having 10 a nozzle, a bursting plug covering the nozzle outlet and exposed to the fluid pressure within the receptacle, an annular cylinder surrounding the nozzle outlet, a piston 15 slidably mounted in the cylinder and bearing against the plug, a pressure relief valve, conduits connecting the receptacle with the relief valve and the annular cylinder, and a drip pipe attached to the 20 conduit connecting the relief valve with the cylinder.

13. The combination with a receptacle

containing fluid under pressure, of a pressure relief device characterized by having 25 a bursting plug exposed to the fluid pressure within the receptacle, fastening means for the plug, and means for exerting an auxiliary pressure against the plug and the fastening means.

14. The combination with a receptacle 30 containing fluid under pressure, of a pressure relief device characterized by having 35 a bursting plug exposed to the fluid pressure within the receptacle, fastening means for the plug, a cylinder located on the pressure side of the plug, a piston 40 slidably mounted in the cylinder and normally bearing against the plug, and means, connected with the receptacle, for exerting a pressure against the piston.

In witness whereof I have hereunto signed my name.

CHARLES C. EGBERT.
